UNITED STATES PATENT OFFICE.

JOSEPH D. BELL, OF SAN FRANCISCO, CALIFORNIA.

REISSUED

COMBINED BED AND SEAT.

1,166,315.

Specification of Letters Patent. Patented Dec. 28, 1915.

Application filed September 7, 1915. Serial No. 49,190.

To all whom it may concern:

Be it known that I, JOSEPH D. BELL, a citizen of the United States, residing at San Francisco, in the county of San Francisco and State of California, have invented new and useful Improvements in Combined Beds and Seats, of which the following is a specification.

The object of the present invention is to provide a combined bed and seat, which is very simple in construction and convenient in operation.

One advantage of the particular construction hereinafter described resides in providing means for guiding the mattress frame into a concealed position without folding it, and so arranging the construction that the mattress frame may, at all times, carry substantially regulation bedding.

Another feature of this particular construction resides in the fact that the two portions of the mattress frame are so arranged as to approximately balance each other whereby, when the swinging seat frame is opened out, only a very slight force is required to extend or retract the mattress frame.

In the accompanying drawing, Figure 1 is a broken plan view of the apparatus when used as a bed; Fig. 2 is a longitudinal vertical section of the same, the wire mattress being omitted; Fig. 3 is a similar view of the same, when used as a chair or davenport; Fig. 4 is a partial similar view of a modified form of the invention; Fig. 5 is a broken view, similar to Fig. 1, showing said modification.

On referring to the drawing, it will be seen that the frame or housing of my improved bed and seat comprises side pieces 1 stiffened by angle-irons or guideways 3, and connected by cross angle-irons 6, 7, a rear upper cross piece 8 and front lower cross pieces 9 and 11. In the inner surfaces of said side pieces are grooves 12.

A seat frame 13 is pivoted to the main frame by pivots 14 and comprises side pieces 16, connected by a front cross piece 17 and 50 a rear cross piece 18, and to which is secured on each side a metallic piece comprising a vertical angle-iron 19, a horizontal angle-iron 21 and an oblique channel-iron 20 or guideway 22, said channel irons being the 55 parts of the seat frame through which the pivots pass. To said seat frame is

pivoted, as shown at 23, a front piece 24, the free end of which, when the device is used as a bed, rests upon the cross piece 11, and, when the device is used as a chair or davenport, fills the opening between the cross pieces 17 and 9. To the main frame is also pivoted, as shown at 26, a back frame 27, which can swing forwardly from a position in which it rests against a stop 28.

A mattress frame 29 is composed of two parts pivoted together, as shown at 31, each part comprising an angle-iron 32 on each side, said angle-irons being connected transversely at the end of the mattress frame by 70 angle-irons 33, 34 respectively. The rear part 36 is carried on each side by two rollers 37, 38, of which the rear roller 37 can roll in the groove 12 in the corresponding piece 2, and the front roller 38 can roll in 75 the channel-iron 22. This channel-iron, in the open position, or that shown in Fig. 2, registers with, or is a continuation of, the angle-iron 3, so that the front roller 38 first rolls in said channel-iron and then on said 80 angle-iron. The front angle-irons 32 travel upon stationary rollers 39 rotatably carried by the horizontal members 21. The front ends of said front angle-irons can run on rollers 35 and their rear ends extend beneath the front ends of the rear angle-irons a sufficient distance to sustain the front ends of the front angle-irons when a weight is superimposed thereon. Pins 40 extending upwardly from the front angle-irons pass 85 through holes in the rear angle-irons. These pins 40 form a second connection between the two angle-irons 32 in addition to the pivot 31 and spaced from said pivot and thereby insure the alinement of the two angle-irons 32 more perfectly than would the pivot 31 alone. The mattress springs 41 are connected to the horizontal members of 90 said transverse angle-irons 33, 34, and since these horizontal members are below the pivotal connections of said angle-irons, the tension of the spring tends to draw the front ends of the front angle-irons downward, and therefore to maintain the wire mattress 95 taut.

42 indicates a loop, the ends of which are attached to the wire mattress frame to hold the stuffed mattress 43, shown in dotted lines, in position.

The manner of conversion of the apparatus from a chair or davenport to a bed, and conversely, is very simple. To move the

device from the position shown in Fig. 3 to the position shown in Fig. 2, the back frame is first swung forwardly and upwardly, then the seat frame is swung forwardly and outwardly into the position shown in Fig. 2, and then the mattress frame is drawn forward into the position shown in said figure. The reverse operation takes place on closing the bed. It will be observed that ample space is provided for containing the mattress in the closed position of the bed and also the pillows and other bedding.

In the modification of the invention illustrated in Figs. 4 and 5, the mattress frame is carried at the rear end upon a shaft 45, the ends of which travel in grooves 47 in said side pieces 1, on the ends of which shaft 45 are pinions 44, which mesh with racks 46 in the grooves 12. This construction insures both sides of the mattress frame traveling at the same speed and renders it unnecessary to apply pressure at the middle of the mattress frame in pushing it back into the closed position.

25 I claim:—

1. A combined bed and seat having a forwardly swinging seat frame, and a mattress frame, the front portion of which is arranged to move forwardly on the seat frame when the latter is in its forward position, and means for guiding the rear portion of said mattress frame upwardly behind the back of the seat.

2. A combined bed and seat comprising a forwardly swinging seat frame having guides extending in the forward position of the seat frame rearwardly and downwardly, a main frame having guides registering with the first-named guides and extending rearwardly and downwardly and also having upwardly extending guides, and a mattress frame having parts movable respectively in the rearwardly and downwardly extending guides and in the upwardly extending guides.

3. A combined bed and seat comprising a forwardly swinging seat frame having guides extending in the forward position of the seat frame rearwardly and downwardly, a main frame having guides registering with the first-named guides and extending rearwardly and downwardly and also having upwardly extending guides, and a mattress frame having parts movable respectively in the rearwardly and downwardly extending guides and in the upwardly extending guides, the front portion of the mattress frame being supported by the seat frame in the forward position of the latter.

4. A combined bed and seat having a swinging seat frame provided with a track, a main frame having a track registering with the first-named track, and a mattress frame guided by said tracks.

5. A combined bed and seat comprising a

reversible seat portion, a movable mattress frame, a track therefor secured below and movable with the reversible seat portion, and stationary tracks therefor beneath the seat portion, said tracks having adjacent ends to form a substantially continuous track.

6. A combined bed and seat comprising a mattress frame having two sections hinged together, one section having extensions past the hinges, said extensions and the other section having, the one pins and the other holes to receive said pins.

7. A combined bed and seat comprising a main frame, a seat frame movably connected thereto, and a mattress frame movable on and guided by said frames and disengaged from said seat frame in the collapsed position of the latter.

8. A combined bed and seat having a reversible seat portion, a movable mattress frame disconnected from said seat portion, and means secured below, and movable with the reversible seat portion for guiding the mattress frame therealong.

9. A combined bed and seat having a reversible seat portion, a movable mattress frame, and a horizontal track for the mattress frame secured below, and movable with the reversible seat portion and engaged by said mattress frame only when the latter moves therealong.

10. A combined bed and seat having a rigid main frame, a forwardly movable rigid frame guided thereby and having fixed thereon tracks located to support and guide both sides of a mattress frame, and a movable mattress frame supported and guided by said frames and tracks, said movable frame being movable independently of the mattress frame.

11. A combined bed and seat having a rigid main frame, a reversible frame pivoted thereto, and a movable mattress frame supported and guided by said frames, said reversible frame being movable independently of the mattress frame.

12. A combined bed and seat having a housing, a pair of guideways therein, a second pair of guideways pivotally connected to said housing to swing about horizontal axes and adapted to be moved into alignment with the first-named guideways respectively, a movable mattress frame and parts connected to said mattress frame and guided by said guideways.

13. A combined bed and seat having a main frame having guideways, a reversible frame pivoted to said main frame, and a movable mattress frame guided by said guideways and supported by said reversible frame in its reversed position and wholly disconnected therefrom in its collapsed position.

14. A combined bed and seat having a housing, a back, a movable seat, and a mat-

tress frame in said housing comprising two pivotally connected unequal sections the shorter section extending within the housing rearwardly beneath the seat and the longer section extending upwardly therein behind the back, said sections being spaced from said seat and back, respectively, a sufficient distance to support thereon suitable bedding, and means operable while the seat is at rest for guiding said sections into alinement with each other.

15. A combined bed and seat having a main frame, a seat frame pivoted thereto, a mattress frame consisting of two pivoted rigid sections, and means for horizontally guiding the pivoted portions of the mattress frame forwardly over the seat in the inverted position of the latter.

16. A combined bed and seat having a housing, a back pivoted thereto, a seat pivoted to the housing at the front edge, a two section mattress frame, a guide extending upwardly behind the back, a separate guide extending forwardly and upwardly beneath the seat, both of said guides being secured

to the housing, the upper end of one section of said mattress frame being guided by said first-named guide, two spaced parts of the other section being guided by the second guide, and a third guide secured to the under side of the seat and arranged to aline with the second guide.

17. A combined bed and seat having a housing, a back, a movable seat, and a mattress frame in said housing comprising two pivotally connected sections extending within the housing, one beneath the seat and the other behind the back, said sections being spaced from said seat and back respectively a sufficient distance to support thereon suitable bedding, and means operable while the seat is at rest for guiding said sections into alinement with each other.

In testimony whereof I have hereunto set my hand in the presence of two subscribing witnesses.

JOSEPH D. BELL.
